UNITED STATES PATENT OFFICE.

HERBERT J. CRABBS, OF PITTSBURGH, PENNSYLVANIA, ASSIGNOR TO WESTINGHOUSE ELECTRIC & MANUFACTURING COMPANY, A CORPORATION OF PENNSYLVANIA.

DISCONNECTING SWITCH.

Application filed November 2, 1921. Serial No. 512,180.

My invention relates to disconnecting switches and, particularly, to means whereby the movable contact member and the stationary contact members may be maintained 5 in alinement.

One of the objects of my invention is to provide means whereby the break jaw of a disconnecting switch which has a bridging structure of considerable length may be brought into proper alinement therewith and inaccuracies of installation compensated for.

Another object of my invention is to simplify the structure and operation of disconnecting switches and to provide means for preventing damage to the stationary contact members by reason of the impact of the movable contact member.

As shown in the accompanying drawing, 20 Figure 1 is a view, in side elevation, of a switch embodying my invention;

Figs. 2 and 3 are fragmentary views taken respectively, from the left-hand side and the right-hand side of Fig. 1;

Figs. 4 and 5 are enlarged views in side elevation and bottom plan, respectively;

Fig. 6 is a view, partially in elevation and partially in section, of one of the stationary contact members;

Figs. 7 and 8 are detail views of a supporting bracket for the jaw members;

Figs. 9 and 10 are detail views of one of the contact-supporting blocks;

Fig. 11 is a plan view of another of the contact-supporting blocks; and

Figs. 12 and 13 are detail views of the bracket which I employ for supporting the devices of Figs. 9 and 11.

My invention is shown as used in connection 40 with a disconnecting switch 14 that is employed to open and to close the circuit through a circuit breaker 15 that may be of any desired type. The disconnecting switch, as ordinarily used, closes the circuit through terminals 16 and 16', bridging members 17 and 18, break jaw structure 19, breaker 15, break jaw structure 20, bridging member 21 and terminal member 16.

The bridging members 17 and 21 are supported from the under side of a panel 24, 50 through insulating pillars 25 and 26. The insulating pillars are provided, as shown more clearly in Fig. 4, with base portions 27 and 28, respectively, that serve as sup-

ports for bracket members 29 and 30, respectively.

The bracket 29 serves both as a hinge jaw for the bridging member 21 and as a support for break jaw members 31 and 32, with which the ends of the bridging members 17 and 18 coact. The bracket members 30 serve as hinge supports for the bridging members 17 and 18 and also support a break jaw 35, with which the end of the bridging member 21 co-operates, and the terminals 16 and 16' are connected to the bracket members 30 and 29, respectively, and to the break jaws 35, 31 and 32, as shown more clearly in Figs. 4 and 5.

In Figs. 7 and 8, I have shown the bracket 30 somewhat in detail, to illustrate more clearly the manner in which the bridging structures 17 and 18 are pivotally supported thereon, holes 37 being provided for the reception of screws 38 (Fig. 5) for supporting 70 the break jaws 35.

The bracket 29 is constructed similarly to the bracket 30 but provision need be made, of course, only for one bridging member to be pivotally supported thereupon.

As shown in Figs. 4 and 5, the bridging members close the circuit directly across the terminal members 16 and 16', while, in the position occupied in Fig. 1, the current is directed through the circuit breaker 15. 85 The circuit breaker 15 is provided with two insulating pillars 39 and 40, upon which break jaws 19 and 20 are mounted. But one break jaw member 20 is required on the pillar 39, for cooperation with the bridging member 21, while two break-jaw members 19 are required upon the insulating pillar 40 to co-operate with the two bridging members 17 and 18.

The pillar 39 (Figs. 1 and 6) is provided with a cap member 42 that serves as a base upon which a bracket 43 is mounted, and the bracket 43, in turn, supports a block 44. The bracket 43 is provided, at its lower side, with slots (Fig. 12) 46, through which pass a pair of bolts 47. When the bolts are loosened, the bracket 43 may be rotatably adjusted upon the base member 42. The insulating pillar 40 is also provided with a base 42, and a bracket 43, mounted thereon, 100 for rotatable adjustment.

The contact-supporting block 44 (Figs. 6 and 11) is provided with a pair of slots 49,

through which extends a pair of bolts 50. These bolts also extend through holes 51 of the bracket 43, and, when loosened, permit the block 44 to be rotatably adjusted upon the bracket 43.

The block 44 is provided with an extended portion 53 that has openings 54 through which bolts may extend to secure break jaws 55 and fingers 56 thereto. A tapped hole 57 is also provided for the reception of a screw 58, which assists in maintaining an arc shield 60 in place.

The break-jaw structure 19 is mounted for rotatable adjustment upon its bracket 43 in the same manner as is the break-jaw structure 20, but, as shown in Figs. 9 and 10, the jaw-supporting block 61 is provided with two arms 63 and 64 for supporting two sets of break jaws 55 and fingers 56, so that the circuit from the terminal 16 to the breaker 15 may be bridged by either the bridging member 17 or the bridging member 18.

It will be seen that, by means of the arrangement illustrated, the circuit through the breaker 15 may be either made or broken without interruption of the main circuit across the terminals 16 and 16'. With the parts in the position shown in Figs. 4 and 5, the blade member 17, for instance, may be brought to the position shown in Fig. 1, and the blade member 21 then also brought to the position occupied by it in Fig. 1. The blade member 18 may then be lowered, and the current thus diverted through the breaker 15 without interruption of the circuit. In cutting out the breaker 15, either of the blades 17 or 18 may be raised to the position shown in Fig. 4, and the other blades then also raised.

The apparatus shown is employed in connection with exceedingly high voltages and is necessarily quite heavy, so that it is sometimes difficult to place the oil-breaker tank in proper alignment with the overhead switch structure. Such alignment is, of course, essential in order that the bridging members 17, 18 and 21 will make proper engagement with the oil-breaker terminals.

By reason of my construction of mountings for the terminals 19 and 20, it is possible to easily bring such terminals into proper alignment with the bridging members. If it were found that the terminal 19 were not directly in position under the pillar 26, in a transverse direction, the bracket 43 could be rotated slightly upon the base member 42, and the block 44 could be rotatably adjusted upon the bracket 43, either to the right or to the left, as required. This double adjustment not only provides for a range of adjustment transversely to the bridging members but also permits the break jaws 55 to be brought into proper alignment with the path of movement of the

bridging members. The terminal member 20 may be also so adjusted.

The fingers 56 are preferably of spring steel and are curved outward slightly at their free ends, so that, if a bridging member should fall from its raised position, its movement would be retarded by the fingers, and excessive shock to the supporting structure for the break jaw members be avoided.

The bridging members are provided with latches 65, of any desired form, and sleet shields 60 and 66 also function in a manner common to devices of this character.

Various modifications may be made without departing from the spirit and scope of the invention, as defined in the accompanying claims.

What I claim as my invention is:

1. In an electric switch, the combination with a movable contact member and a stationary contact member, of a rotatably adjustable support for the stationary contact member, and means whereby the stationary contact member may be rotatably adjusted upon the said support, the rotatable adjustments being made in approximately parallel planes.

2. In an electric switch, the combination with a movable contact member, of a stationary contact member, a base member, a bracket member rotatably adjustable on the base member, and a stationary-contact-supporting member mounted for rotative movement eccentrically of the bracket.

3. In an electric switch, the combination with a movable contact member and a stationary contact member, of a base, a bracket rotatably supported upon the base and having a portion extending radially thereof, and a contact-supporting block rotatably adjustable upon the said extended portion, the rotatable adjustments being made in approximately parallel planes.

4. An adjustable contact member comprising a base member, a bracket member provided with a plurality of curved slots, clamping means passing through the slots in said bracket member and engaging said base member, a supporting member provided with a plurality of curved slots mounted on said bracket member, clamping means passing through the slots in said supporting member and engaging said bracket member, and a break jaw mounted on said supporting member.

5. An adjustable contact member comprising a base member, a break-jaw member, and an intermediate connecting means, said connecting means being provided with means whereby said break jaw is capable of rotatable adjustment about said base member in a plurality of planes extending in approximately the direction of the longitudinal axis of the base member.

6. In an electric switch device, the com-

bination of a supporting member, a fixed contact, an adapter for supporting said fixed contact and means for securing said adapter to said member in various positions 5 of angular adjustment.

7. In an electric switch device, the combination of an inclined supporting member, a washer secured thereto, a fixed contact, an adapter adjustable on said washer for 10 supporting said fixed contact, and means for clamping said adapter to said washer in adjusted position.

8. In an electric switch device, the combination of a supporting insulator bushing, 15 an annular member at the end thereof,

means for rigidly securing said member to said bushing, a fixed contact, an adapter for supporting said fixed contact in a substantially vertical position and means for clamping said adapter to said member in 20 various positions of angular adjustment.

9. In an electric switch device, the combination of an insulator bushing, an adapter carried thereby, a contact retainer and means for adjustably securing said contact 25 retainer to said adapter.

In testimony whereof, I have hereunto subscribed my name this 29th day of October, 1921.

HERBERT J. CRABBS.
